D11-79. OR D11,716 EX

Mar. 30, 1880,

UNITED STATES PATENT OFFICE.

FRANCIS DIMIER, OF NEW YORK, N. Y.

DESIGN FOR JEWELRY-PENDANTS.

SPECIFICATION forming part of Design No. 11,716, dated March 30, 1880.

Application filed February 26, 1880. Term of patent 3½ years.

To all whom it may concern:

Be it known that I, FRANCIS DIMIER, of the city, county, and State of New York, have invented a Design for Jewelry-Pendants, of which 5 the following is a specification.

The accompanying photograph fully represents my design, in which a front view is shown of a pendant of my design.

Pendants for ear-rings, brooches, and other 10 articles of jewelry have been made in various forms; and my design consists in a new form or configuration of such pendants, said design being a fleur-de-lis and a crescent arranged as shown and next described.

15 *a* is the crescent, and *b* the fleur-de-lis. The horns of the former are elongated and the fleur-de-lis attached within the crescent, the head

or point *c*, by which the pendant is hung, projecting above the horns.

The pendant may have a surface ornamentation of any desired character and is preferably studded with diamonds. 20

I claim as my invention and desire to secure by Letters Patent—

The design for jewelry-pendant, the same 25 consisting of the crescent-shaped piece *a*, with the piece *b*, in the shape of a fleur-de-lis, fitted within the crescent, substantially as shown and described.

FRANCIS DIMIER.
